Primary Examiner — Tamara L Hahn

(57) **CLAIM**

The ornamental design for a folding ramp, as shown and described.

DESCRIPTION

FIG. 1 is a perspective view of a folding ramp showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof; and,

FIG. 9 is an enlarged view of the encircled portion in FIG. 1.

The dash-dot lines in FIG. 1 and FIG. 9 illustrate the boundaries of the enlarged view indicators and form no part of the claimed design.

1 Claim, 9 Drawing Sheets
